Attorney

UNITED STATES PATENT OFFICE.

ELISHA N. FALES, OF DAYTON, OHIO.

VEHICLE HEATER.

Application filed June 29, 1921. Serial No. 481,305.

To all whom it may concern:

Be it known that I, ELISHA N. FALES, a citizen of the United States, residing at Dayton, in the county of Montgomery and 5 State of Ohio, have invented certain new and useful Improvements in Vehicle Heaters, of which the following is a specification.

This invention relates to heaters in general and more particularly to a heater designed 10 to derive its heat from the exhaust gases of an internal combustion engine.

While the adaptation of my invention as shown here is disclosed as depending more particularly on the heat from the exhaust 15 gases of an internal combustion engine it will be obvious that I do not limit my invention to such application as the device is applicable to any system where the gases which are to be the source from which heat 20 is to be derived, whether exhaust or other gases, are moving at an appreciable velocity.

It is the general purpose of my invention to utilize a simple phenomenon of aerodynamic forces to provide for the circulation 25 of heating gases through a heater.

It is the particular purpose of my invention as disclosed to utilize this aerodynamic phenomenon to provide for the circulation of the exhaust gases of an internal combustion 30 engine or the like through a heater. This heater may be used to warm an interior compartment of an automobile, aircraft, motor vehicle or may be used to warm any part of the same, as for instance the water of the 35 cooling circulation system or the intake manifold of the engine of such a vehicle.

Other and more specific objects of my invention will be found in the accompanying specification as it progresses and will be disclosed in the accompanying drawings, in 40 which—

Fig. 1 is a vertical sectional view through the compartment to be heated showing the two positions of the heater in elevation.

Figure 2 is an enlarged section through the heater, supply pipe and the inlet and exhaust pipes showing the heater in position (heat on).

Figure 3 is a plan view of the device as shown in Fig. 1 showing the heater in inoperative position (heat off).

Figure 4 is another modification showing inlet and exhaust pipes from heater as distinct and separate.

Referring in detail to the drawings it will be noted that like reference numerals will

be used for like parts in the various modifications in which 1 represents the wall of the craft, vehicle or device to be heated. 2 is a heater of any approved type. 3 is a pipe 60 through which the gases which are to act as the source of heat are passing in the direction indicated by the arrow. In this particular case let us consider 3 to be the exhaust pipe of an internal combustion engine. 65

In the embodiment as shown in Figures 1, 2 and 3, around or through the exhaust pipe 3 there is provided a suitable plug 11 adapted to act as a bearing for the pipe 6. Pipe 6 is rotatably mounted in this bearing 70 and has an arm 6^a integral therewith or secured in any approved manner to the bearing portion of pipe 6 and extending at right angles thereto.

The arm 6^a is rigidly secured in any approved manner to a heater 2 for which it acts as a support. This arm 6^a is provided with a port 7, which opens into pipe 3, while the opposite end opens into the heater through exhaust port 7^a. The heater is 75 adapted, when out of action to rest within a recess 8 of wall 1 and is separated therefrom by fireproofing material 9. When it is desired to move the heater into operating position the handle 10 is grasped and the 80 heater moved out of the recess, the heater rotating on arm 6^a around the center of the bearing portion of pipe 6.

Centrally mounted within pipe 6, is a second and smaller pipe 4 which extends substantially the length of said pipe 6 reaching to a point 4^a well within the interior of the heater and has at its other end an elbow opening into pipe 3 in a direction diametrically opposite port 7. Pipe 4 will hereinafter be referred to as the inlet pipe and pipe 6 as the outlet pipe.

Reference to Figure 3 will disclose the fact that when the heater is out of operative position the inlet pipe faces at right angles 100 to the flow of gas through the pipe 3 with the result that there is no flow of gas through pipe 4. The rush of gases past the port 5 of pipe 4 would in fact create a slight suction therein rather than causing a flow 105 of gases into said pipe. The outlet pipe 6 would have its port 7 at a point diametrically opposite and the result of these two suction effects would be merely a low pressure in the heater with no heating effect produced.

When the heater is rotated into operative

position however it will be noted that the inlet port 5 faces upstream of the flow of the gases in the supply pipe 3 causing a rush of gases through pipe 4 to the heater with the desired results. The port 7 of the outlet pipe 6 will at the same time be swung into a position facing down stream of the exhaust with the result that the rush of gases in the supply pipe past said port will create a low pressure area in the pipe with the result that the circulation of the gases through the heater will be further insured.

In the modification shown in Fig. 4 the heater is stationary and the inlet pipe 4' rotatably bears in a bearing plug 11 in the exhaust pipe 3 and a bearing 12 in the heater. It is provided with a handle 10' to provide for its rotation when desired to throw the heater into or out of action. The outlet pipe 6' is fixedly mounted and extends rearwardly with its outlet always facing down stream of the air flow past the moving vehicle having no contact with pipe 3.

I claim:—

- 25 1. In combination with a supply pipe for hot gases in motion, a heater, and means for conducting the gases back and forth between said supply pipe and heater embodying inlet and outlet pipes having ports in constant communication with said supply pipe and adapted to be turned into and out of line with the flow of gases through said supply pipe.
- 30 2. In combination with a supply pipe for hot gases in motion, a heater, and means for conducting the gases back and forth between said supply pipe and heater embodying in-

let and outlet pipes arranged one within the other having ports in constant communication with said supply pipe and adapted to be turned into and out of line with the flow of gases through said supply pipe.

3. In combination with a supply pipe for hot gases in motion, a heater, and means for conducting the gases back and forth between said supply pipe and heater embodying inlet and outlet pipes having ports in constant communication with said supply pipe and adapted to be turned into and out of line with the flow of gases through said supply pipe and means for turning said inlet and outlet pipes.

4. In combination with a supply pipe for hot gases in motion, a heater, and means for conducting the gases back and forth between said supply pipe and heater embodying inlet and outlet pipes having ports in constant communication with said supply pipe, said ports facing in diametrically opposite directions, and adapted to be turned into and out of line with the flow of gases through said supply pipe.

5. In combination with a supply pipe for hot gases in motion, a heater, and means for conducting the gases back and forth between said supply pipe and heater embodying inlet and outlet pipes having their inlet and outlet ends provided with ports facing in diametrically opposite directions and adapted to be turned into and out of line with the flow of gases through said supply pipe.

In testimony whereof I have affixed my signature.

ELISHA N. FALES.
